UNITED STATES PATENT OFFICE.

FREDERICK W. HUESTIS, OF BOSTON, MASSACHUSETTS.

DESIGN FOR A TIRE FOR WHEELS.

SPECIFICATION forming part of Design No. 30,416, dated March 28, 1899.

Application filed February 24, 1899. Serial No. 706,736. Term of patent 14 years.

To all whom it may concern:

Be it known that I, FREDERICK W. HUESTIS, a citizen of the United States, residing at Boston, in the county of Suffolk and State of Massachusetts, have invented a certain new and useful Design for Tires for Wheels, of which the following is a specification, reference being had therein to the accompanying drawings.

10 Figure 1 is an elevation of a tire, showing my new design. Fig. 2 is a sectional view taken on the line 2 2 of Fig. 1. Fig. 3 is a sectional view taken on the line 3 3 of Fig. 1.

15 As shown in the drawings, the leading or material feature of my design consists of the shape of the inner portion of the tire, the base E thereof being made up of rectilinear elements which form a cylinder, and the sides D D thereof also being made up of rectilinear

elements, as is clearly shown in the sectional views, Figs. 2 and 3. The outer portion of the tire is formed of a series of elevations A, separated from one another by depressions B, and the elevations A are of a shape approaching that of a segment of an ellipsoid, as shown, 25 the longest axis of said ellipsoid being in the direction of the circumference of the tire.

Having described my invention, what I claim as new, and desire to secure by Letters Patent, is—

30 The design for a tire for wheels, as herein shown and described.

In testimony whereof I affix my signature in presence of two witnesses.

FREDERICK W. HUESTIS.
